Des. 192,883
Patented May 22, 1962

192,883

SUNGLASS FRAME OR THE LIKE

Albert C. Petitto, Hudson, Mass., assignor to Foster Grant Co., Inc., Leominster, Mass., a corporation of Delaware

Filed Dec. 20, 1960, Ser. No. 63,276

Term of patent 14 years

(Cl. D57—1)

The rear not shown is substantially plain and conventional.

I claim:

The ornamental design for a sunglass frame or the like, substantially as shown and described.
